UNITED STATES PATENT OFFICE.

CHARLES W. MABEY, OF INDIANAPOLIS, INDIANA.

GLUEPOT.

1,376,823.

Specification of Letters Patent.

Patented May 3, 1921.

Application filed June 14, 1920. Serial No. 388,756.

To all whom it may concern:

Be it known that I, CHARLES W. MABEY, a citizen of the United States, residing at Indianapolis, in the county of Marion and 5 State of Indiana, have invented certain new and useful Improvements in Gluepots, of which the following is a specification.

This invention relates to a portable electrically heated glue-pot; and one of the 10 principal objects of the invention consists in the provision of a glue-pot of the above character which, as a self-contained unitary structure, is simple in construction, highly efficient in heat retaining properties, and one 15 in which many of the objectionable features associated with the use of the old and well known styles of glue-pots are eliminated.

A further object of the present invention consists in the provision of means for enabling the easy replacement of the heating 20 elements when the same have become unfit for further use, and further, to enable the character of the heating elements to be readily changed so as to adapt the glue-pot 25 to the use of electric currents of different potential values. As an illustration, when a workman moves from one job where an electric current of a given potential value is employed to a point where a current of a 30 different potential value is used.

The present invention particularly resides in the ready adaptation of the present glue-pot to the use of electrical currents of different potential values, together with such 35 structural advantages which possess to a large degree the elements of heat retaining efficiency and economy.

The above objects, together with such others as may appear from a perusal of the 40 following description and claims, are attained by means of the construction illustrated in the accompanying drawings, forming a part hereof, in which—

Figure 1 is a fragmentary detail plan 45 view of my improved glue-pot with the cover omitted. Fig. 2 is a view partly in side elevation and partly in vertical section of the glue-pot.

Referring to the drawings, the external 50 appearance of the present glue-pot is similar to that of an ordinary culinary pail or bucket, consisting of an outer shell or casing 10, having its upper edge bent outwardly into a horizontal flange 11. As shown, casing 10 is open at its lower end. Into the upper end of casing 10 I insert an interme-

diate receptacle 12, which is of less diameter than casing 10, so as to provide an intervening chamber between the outer periphery of receptacle 12 and the inner periphery 60 of casing 10. Into this chamber I introduce a comparatively thick insulation 14 for reducing the radiation of heat to a minimum. The upper edge of receptacle 12 is bent outwardly and thence downwardly into the 65 outwardly disposed incline 16 where it terminates in a flange 15. Flanges 11 and 15 are held apart by suitable insulating material 17 so as to prevent the heat from within the glue-pot from affecting the outer 70 casing 10. Flanges 11 and 15 are properly secured together by the screw-bolts 18. A pair of eye-bolts 19 are passed through flanges 11 and 15 to provide means for attaching the ends of a bale 20, whereby the 75 glue-pot is rendered portable.

Attached to the inner periphery of insulation 14 in any suitable manner is a thimble 21 which extends below the bottom of receptacle 12 and forms a chamber for the reception of a circular disk 22—usually composed of clay or similar material—which carries the heating elements, to be hereinafter described. Thimble 21 adds efficiency to the heat retaining properties of the glue-pot, by 85 assisting in so confining the heat within the glue-pot that the temperature within the pot is raised more rapidly and thereby correspondingly shorten the time required for reducing the glue to a liquid state, than 90 obtains in the old forms of glue-pots. As before stated, disk 22, which is preferably a clay product, forms a base for mounting the heating elements. These heating elements comprise a plurality of columns of finely 95 coiled wires 23 which columns rest within suitable channels 24 formed in the upper face of disk 22. Columns 23 may be connected in series in order to vary the character of the heat temperature. Columns 23 100 are connected to a switch 25 by which the electric current entering through conductor wires 26 may be regulated. Disk 22 is held in operative position, so as to bring heating elements 23 into close proximity to the bottom of receptacle 12, by means of a nut 30 which is arranged on a single threaded bolt 31 which is located centrally in the floor of receptacle 12. To further retard radiation 105 of heat from the interior of the glue-pot I 110 introduce into the lower open end of casing 10 an insulating disk 32 which is also re-

tained in position by a nut 33 on bolt 31. It will be observed from the foregoing description that, after the heating elements 23 become worn and unfit for further service, or 5 when it is desired to change and thereby adapt said heating elements to an electric current of a different potential value, their replacement can easily be effected by simply removing nut 33 and insulating disk 32 10 from bolt 31 and then remove nut 30 from bolt 31 and nut 35 from terminal 36.

The inner receptacle 40 for holding the glue material is preferably composed of copper and is arranged in the hollow chamber 15 of receptacle 12. As shown in Fig. 2, glue-pot 40 is supported by the flanged portion of receptacle 12 so that the bottom of receptacle 40 will stand sufficiently above the floor of receptacle 12 to provide an intervening dry air chamber 41 which reduces the liability of the glue becoming overheated, without the use of water as obtains in the old and well-known glue-pots. The inner receptacle 40 is formed so that the 20 diameter of its upper end will close the upper end of the chamber in receptacle 12, the wall of receptacle 40 then tapering inwardly toward its bottom, so as to form an annular air space 42 between it and receptacle 12. Air space 42 is wedge shaped in cross section and is an extension of air chamber 41, so that the dry air chamber 41 extends around the exterior surface of inner receptacle 40. The upper edge of receptacle 25 is formed uniquely so as to overcome certain objections which attend the use of the old forms of glue-pots. In the prior devices, the liquid glue worked its way over the upper edges of the inner receptacles 30 and ran over the meeting edges of the inner and outer receptacles until the two became so adhered together as to render it quite difficult to separate them. In the present device the possibility of the glue working 35 over the broad flaring edge of the inner receptacle 40 is reduced to a minimum. This is accomplished by bending the metal adjacent the upper edge of the inner receptacle into a long outwardly sweeping 40 curve, as at 44, and at the outer end of the curve the metal is abruptly bent downwardly into a perpendicular flange 45 so that little or no surface is exposed to cause the liquid glue to flow outwardly. In addition to the 45 wide sweeping curve 44 imparted to the upper edge of inner receptacle 40 for draining the liquid glue which may accidentally fall upon said curved surface back into the glue-pot, I also provide a wiper-rod 47 50 whereby any excess of liquid glue may be removed from the brush as the latter is withdrawn from the inner receptacle by the operator. This wiper-rod 47 is positioned relatively to receptacle 40 so that 55 there remains little likelihood of any of the

excess glue alighting upon curved surface 44, if the operator exercises a little care in wiping his brush. As shown in Fig. 1, wiper-rod 47 extends transversely across the top of the glue-pot, and comprises, preferably, a hollow rod the hollow portion of which is adapted to receive the free ends of a bale 50 by which the inner receptacle 40 may be removed and replaced without disturbing the remaining parts of the device. Bale 50 is mounted in ears 51 which are arranged at opposite sides of receptacle 40, and the bale being made of spring wire may be expanded to free its ends from ears 51 and thereby cause the release of wiper-rod 47, when it is desired to disconnect the parts. 70 75 80 85

The device is also provided with a cover 55 which is hinged to receptacle 12 by means of a hinge 56. As shown, cover 55 is of sufficient width and depth to completely inclose the upper end of the inner receptacle 40 of the glue-pot. Cover 55 also is formed for the purpose of reducing, as far as possible, many of the annoyances accompanying the use of the old-style glue-pots. It will be noted that the metal lying along the upper marginal edge of the cover is bent to form a semi-circular roll 57 and that the central portion of the cover is arched up 90 as at 58 independently of roll 57. On the lower surface of the cover a rib 59 is formed at the point of meeting of the surface planes of the parts 57 and 58, and rib 59 is positioned to be within a vertical plane that 95 coincides with the inner periphery of receptacle 40. Consequently, when sufficient steam has condensed or collected along the under surface of the central portion 58 of the cover to cause the collected water to be 100 effected by gravitation the curved surface 58 will convey the condensed water to rib 59 where it discharges back into the inner receptacle 40, and prevents the water from being discharged outside of the device. 105 110

Having thus fully described my said invention, what I desire to secure by Letters Patent, is—

1. A glue-pot of the character described, 115 an open bottom casing, an intermediate receptacle arranged within the hollow portion of the casing and supported by the latter, a glue holding receptacle introduced into the hollow portion of the intermediate receptacle, a removable heating element supporting means arranged against the bottom of the intermediate receptacle, and means for removably securing said preceding means in operative position.

2. A glue-pot of the character described, 125 an open bottom casing, an intermediate receptacle arranged within the hollow portion of the casing and supported by the latter, a glue holding receptacle introduced into the hollow portion of the intermediate recept- 130

tacle, a heating element arranged to contact the bottom of the intermediate receptacle, and a removable support for maintaining the heating elements in close proximity of the bottom of the glue holding receptacle.

5. A glue-pot of the character described, an open bottom casing having its upper edge terminating in a radial flange, a thimble of less diameter than the casing inserted into the latter, a non-conducting heat element introduced into the space intervening the thimble and casing, an intermediate receptacle inserted into the hollow portion of the thimble and having its upper edge terminating in an outwardly and downwardly disposed flange which rests upon the casing flange, and means for securing the two flanges together.

10. A glue-pot of the character described, an open bottom casing, an intermediate receptacle arranged in and supported by said casing, a removable glue holding receptacle arranged in and supported by said intermediate receptacle, a brush-wiper rod arranged across the open mouth of the glue

15. holding receptacle, a heating element arranged to contact the bottom of the intermediate receptacle, a support for supporting the heating elements removably arranged in the open end of the casing, and means for 30 removably securing said support in operative position.

20. 5. A glue-pot of the character described, an open bottom casing, an intermediate receptacle arranged in and supported by said 35 casing, a removable glue holding receptacle arranged in and supported by said intermediate receptacle, and a cover hingedly secured to the casing for closing the open end of glue holding receptacle, the central portion of the cover being arched upwardly and within the confine of the glue holding receptacle for draining back the excess of water accumulated on the under side of the cover into the glue holding receptacle. 40

25. In witness whereof I have hereunto set my hand and seal at Indianapolis, Indiana, this 9th day of June, A. D., one thousand nine hundred and twenty.

CHARLES W. MABEY. [L. S.]
